United States Patent Office.

JAMES PATTERSON ROBBINS, OF PHILADELPHIA, PENNSYLVANIA.

Design No. 3,674, dated September 28, 1869.

DESIGN FOR A SET OF HARNESS-MOUNTINGS.

The Schedule referred to in these Letters Patent and making part of the same.

I, JAMES PATTERSON ROBBINS, of the city of Philadelphia, and State of Pennsylvania, have invented and produced a new and original Design for Harness-Mounting, of which the following is a specification.

The nature of my design is fully represented in the accompanying photographic illustration, to which reference is made.

Figure 1 represents the saddle-hook;
Figure 2 is the post-pad hook;
Figure 3 is the post-fly hook;
Figure 4 is the terret;
Figure 5 is the fly-terret; and
Figure 6 is the saddle-bolt hook.

In the several figures, the open parts *a*, which receive the lines, are of octagon-form, the said form being interrupted, or broken, only at the points *b*, in figs. 1, 2, 3, and 6.

In said parts *a*, every other corner or side of the octagon is straight, and the intermediate sides formed of an arc of a circle, as represented.

In fig. 1, the part *a* has an immediate connection

with the bolt or shank-part *c*, but in figs. 2, 3, 4, and 5, the pedestals *d* connect the parts *a* and *c*.

Fig. 3 has an ornamental head, *e*, in connection with the stem *f*, which projects upward from the part *a*.

The said head *e*, and fly *g*, in connection therewith, are of correspondent octagon-form to the part *a*. Their position is at right angles to the said part *a*.

The fly *g* has four openings, *h*.

In fig. 5, the fly *g'* is of the same form as the part *a*, in which it is situated, and has four openings, *h'*.

In figs. 1 and 2, there are scroll-formed projections, *i*, from the parts *a*.

What I claim as my invention, and desire to secure by Letters Patent, is—

The design for harness-mounting, as shown.

In testimony whereof, I have signed my name to this specification, this 27th day of August, 1869, in the presence of the following witnesses.

JAMES PATTERSON ROBBINS.

Witnesses:

STEPHEN USTICK,
JOHN WHITE.
